SHOPPING BAG

Ela D. Story, Tyler, Tex.

Application October 3, 1929, Serial No. 397,115
Renewed June 2, 1933

1 Claim. (Cl. 150—1.7)

The invention relates to bags for carrying groceries and other articles conveniently, and has for its object the provision of an improved bag of the character stated that is strong in construction to be adapted for carrying heavy loads, and in which provision is made for distributing the lift on the hand-holds over the sides of the bag and remote from the hand-holds to prevent tearing out at the hand-holds in lifting heavy loads in the bag.

A further object of the invention is the provision of a bag in which the two sides that are secured together by seams are overlapped to provide superposed layers forming the bottom of the bag, and in which the material of the sides of the bag at the open end thereof are folded inwardly and secured to the respective sides of the bag and provided with means forming hand-holds, and providing reinforcing strips secured to the folded portion at the contiguous side of the bag that are crossed over the openings, said strips providing reinforcements for the hand-holds and serving to distribute the lift from the hand-holds to parts remote therefrom.

The invention will be described in detail hereinafter and will be found illustrated in the accompanying drawing in which

Figure 1 is a side view in elevation of the improved shopping bag,

Figure 2 is a transverse sectional view on a plane indicated by the line 2—2 of Figure 1,

Figure 3 is a fragmentary sectional view on a plane indicated by the line 3—3 of Figure 2,

Figure 4 is a transverse sectional view on a plane indicated by the line 4—4 of Figure 1, and

Figure 5 is a detail sectional view on a plane indicated by the line 5—5 of Figure 3.

In the drawing similar reference characters are used to designate corresponding parts throughout the several views.

As shown in the drawing the bag is formed of two pieces of material, designated 1 and 2, respectively, said material being canvas or other suitable material, and is joined in tubular form by overlapped seams 3 preferably by two rows of stitching 4. The material of the sides 1 and 2 is overlapped to form the bottom of the bag as shown at 5 and 6, the lap 5 being a continuation of the side 1 and has an upwardly extended portion 5^a secured on the inner side of the bag to the side 2, while the lap 6 is a continuation of the side 2 and has an upwardly extended portion 6^a secured to the outer side of the side 1. Lap 5 is also provided with inwardly and upwardly extended flaps or extensions 5^b, and lap

6 with flaps or extensions 6^b that are secured to the sides 1 and 2 to reinforce the bottom of the bag at the seams 3, this structure, obviously, making a very strong bottom for the bag to enable it to be used for carrying heavy loads.

Before closing the seams 3 at the top of the bag, the material of the sides 1 and 2 is folded inwardly as shown at 7 and 8, respectively, the corners of the folded portion being again folded under the folds 7 and 8 as shown at 7^a and 8^a,

respectively. The folded portions 7 and 8 and the sides 1 and 2 are provided with openings 9 and 10, the material cut out by the formation of the openings in the folded portions 7 and 8 being folded around the edges of the upper parts of

the openings 9 and 10 and secured by means of stitching through the underlying portion to provide hand-holds, the folded portions being designated 11 and 12, respectively. To reinforce the hand-holds, previous to folding the portions 7 and 8 inwardly, as heretofore described, strips of

canvas or other material are secured to the material of the sides 1 and 2 in crossed relation so that the crossed portions of the strips are arranged above the hand-holds, said strips being

designated 13 and 14 respectively for the two sides of the bag, 15 and 16 designating rows of stitching securing said strips to the material of the bag. By the provision of these strips and the arrangement of them relatively to the hand-holds, and the securing of the strips to the bag

in the manner stated, it will be apparent that when a lift is made on the hand-holds 11 and 12, that the lift will be distributed by means of the strips to the remote portions of the sides 1 and 2

at the two sides of the hand-holds, and furthermore that the strips will serve to reinforce and strengthen the bag at the hand-holds. To further reinforce the upper portion of the bag at

the hand-holds, a filler strip 17 is provided on each side of the bag within the crease of the fold formed by folding the portions 7 and 8 inwardly, and said filler strips extend to the secured edges of the material of the sides where joined by the seams 3, and are secured in the seams, as shown

in Figure 4, this structure also strengthening the upper portion of the bag at the hand-holds.

In using the bag for carrying articles, it will be apparent that if the contents of the bag permits that the flexibility of the bag will allow the top of the bag to be collapsed so that the two sides

may be brought together and the bag carried by grasping the two hand-holds by a single hand. In event the material carried by the bag will

not permit collapsing, it will be apparent that

the bag may be carried by inserting a rod through the hand-holds to permit carrying by two persons if so desired or by a single person, or the bag may be carried by grasping a single hand-hold. It will be apparent, however, that because of the reinforcement of the hand-holds in the manner hereinbefore described that the bag is capable of carrying a heavy load without endangering tearing out at the hand-holds because 10 of the burden borne.

What is claimed is:—

A shopping bag, comprising a body portion consisting of pieces of material providing the sides of the bag and secured together by stitching 15 through overlapped edges of said pieces, the

pieces of material at the top or mouth of the bag folded inwardly and secured to the respective pieces forming the sides, the material of the body portion and of the turned portions provided with aligned openings forming hand-holds, 80 a filler strip of material secured in the fold of each turned portion, and other strips secured between the body and turned portion and crossed above said hand-holds, said filler strip and other strips providing reinforcements for the hand-holds and providing means to distribute the weight of the bag and its contents to portions remote from said hand-holds.
